Patented Feb. 6, 1917.

UNITED STATES PATENT OFFICE.

KARL EGGART, OF ARBON, SWITZERLAND, ASSIGNOR TO THE FIRM OF ADOLPH SAURER,
OF ARBON, SWITZERLAND.

EMBROIDERING-MACHINE.

1,214,525.

Specification of Letters Patent.

Patented Feb. 6, 1917.

Application filed October 2, 1915. Serial No. 53,675.

To all whom it may concern:

Be it known that I, KARL EGGART, a subject of the Emperor of Germany, and a resident of Arbon, Switzerland, have invented 5 new and useful Improvements in Embroidering-Machines; and I do hereby declare the following to be a full, clear, and exact description of the invention, such as will enable others skilled in the art to which it 10 appertains to make and use the same, reference being had to the accompanying drawings, and to letters or figures of reference marked thereon, which form a part of this specification.

15 This invention relates to means for suspending the fabric frame or work frame in a shuttle embroidering machine, in which the frame is movably supported not only at its ends but at at least one intermediate point, 20 and flexible tension members are provided for the transmission of movement from one support to another in such manner that the several supports shall have equal movement. In such a suspension system each flexible 25 member is fastened at one end to the corresponding, vertically moving support and at the other end to a pulley, the rotating motion of which is to be converted into the rectilinear motion of the support. Each verti-

30 cally movable support must have a length proportionate to the extent of movement of the flexible tension member and each support, particularly each intermediate support, has heretofore had a width determined 35 by the combined width of the three flexible members which are found at this point. Again, the arrangement heretofore employed, involving three tension members alongside one another, has also involved the 40 use of correspondingly broad pulleys at the ends of the frame. By reason of the use of a broad and therefore heavy intermediate support and of broad pulleys at the ends there has been a great deal of dead weight 45 in the suspension system, the inertia and momentum of which have to be overcome in the frequent and rapid reversals of movement of the fabric frame in the operation of the embroidering machine. The tendency at the 50 present time is to increase the speed of operation of embroidering machines and with such increase the overcoming of inertia and momentum of so much dead weight is a serious disadvantage.

55 It is therefore the object of this invention

to overcome these disadvantages by reducing as much as possible the dead weight of the suspension mechanism and in accordance therewith the pulleys, the flexible tension members and supports are combined and 60 arranged as hereinafter described so as to reduce to a minimum the dead weight of the suspension system.

The invention will be more fully explained hereinafter with reference to the accompanying drawing in which it is illustrated somewhat diagrammatically and in which,—

Figure 1 is a view in front elevation showing a portion of the frame of an embroidering machine, the fabric frame and the suspension system. Fig. 2 is a top view of the part shown in Fig. 1. Fig. 3 is a top view of some of the parts shown in Fig. 2, other parts being omitted for the sake of clearness. 70 Fig. 4 is a detail view in section on the plane indicated by the line A, B of Fig. 1, but on a larger scale, looking in the direction of the arrows. Fig. 5 is a detail view in section 75 on the plane indicated by the line C, D of Fig. 1, also on a somewhat larger scale, looking in the direction of the arrows. Fig. 6 is a view in elevation illustrating a modification to be referred to.

80 In the drawing the main frame of a shuttle embroidering machine is indicated at 1 and the fabric frame at 2. The latter is capable of movement both horizontally and vertically and is supported, through plane horizontal surfaces, upon rollers 5, 5 at its 85 ends and upon a roller 5' at an intermediate point, the rollers being carried upon vertically movable supports 3, 3' and 4. Movement in a vertical direction is imparted to the supports 3, 3' and 4 from an automat or jacquard mechanism 16 through the devices about to be described, and horizontal motion is imparted to the fabric frame 2, also from the automat or jacquard mechanism, 90 through devices of any suitable character, 95 not shown herein. Each support 3, 3' may be guided in its vertical movement by guide wheels 21 on the main frame, the support 4 being similarly guided by guide wheels 25 100 on the main frame. The support 3' has secured to it one end of a flexible tension member 13, the other end of which is secured to a pulley 12 supported on the main frame. Another flexible member 14 (or, it might be, 105 an extension of the flexible member 13), is 110

also secured to the pulley 12 and has connected thereto a weight 15 to counterbalance, through the connections hereinafter described, the weight of the fabric frame 2.

5 An endless flexible tension member 10 passes over and is secured to the pulley 12 and a wide pulley 6 which is mounted on a member 19 of the frame 1. The endless flexible tension member 7 passes over and is 10 secured to the pulley 6 and a pulley 8 which is mounted on a suitable bracket 23, the tension member 7 being secured to the support 4 at 20. An endless flexible tension member 9 also passes over and is secured to 15 the pulley 6 and a pulley 11 which is mounted on the main frame at the end of the machine and has secured thereto a worm wheel engaged by a worm, as at 22, the worm being actuated in the usual manner by the 20 automat or jacquard mechanism 16. It will be observed that the two pulleys 6 and 8, constituting members with curved surfaces, have a common vertical tangent in the plane of movement of the intermediate support 4. 25 A flexible tension member 17 is secured to the pulley 11, passes over the guide pulley 18 and is secured to the vertically movable support 3, the member 17 being led from the under side of the pulley 11 so that although 30 the pulleys 11 and 12, rotating in the same direction, are mounted on opposite sides of the corresponding supports 3 and 3', the supports shall move up or down together.

In the construction shown in Fig. 1 of 35 the drawings a counterbalance weight 15 is connected to the pulley 12 by a flexible tension member 14, but in the construction shown in Fig. 6 a counterbalance spring is substituted for the weight. As shown therein, a torsion spring 26 acts upon a lever 27 to which the tension member 14 is connected. The other end of the spring 26 is connected with worm-gearing 28 by means of which the tension of the spring can be regulated. 40 It will be observed that through the employment of an endless tension member 7 for the support 4 the latter can be made narrow and consequently light, while the pulley 6 can also be made appreciably narrower. Moreover, the flexible members 9 and 10 can be arranged in such a way that the parts thereof which lie between the respective pulleys are in parallel relation, rendering possible a light construction of 45 parts of the suspension system. Again, by this arrangement, only two widths of tension members 9 and 10 for the outer movable supports, must be accommodated on the pulley 6 in addition to the tension member 50 7, while only two breadths of tension members must be accommodated on the pulleys 11 and 12. The pulleys 6, 11 and 12 may therefore be kept narrower than is usually the case in suspension systems of this type. 55 The limitation of dead weight to the mini-

70 mum, which is effected by the arrangement described, is of material advantage in the operation of high speed machines, reducing considerably, as it does, the mass which is to be set in motion at every operation and frequently to be reversed in motion.

I claim as my invention:

1. In an embroidering machine, the combination of a main frame, a fabric frame, vertically movable end supports and a vertically movable intermediate support, all guided on the main frame and supporting the fabric frame, pulleys adjacent to the end supports, a flexible connection between each end pulley and the corresponding support, a 75 80 85 movable member provided with a curved surface adjacent to the intermediate support, a second movable member also provided with a curved surface mounted on the main frame, said two members having a common vertical tangent, a flexible connection secured to said two members and the intermediate support and endless flexible connections between the end pulleys and said member arranged adjacent the intermediate support. 90

2. In an embroidering machine, the combination of a main frame, a fabric frame, vertically movable end supports and a vertically movable intermediate support, all 95 100 105 guided on the main frame and supporting the fabric frame, a pulley adjacent to one of the end supports, a pulley adjacent to the intermediate support, a driving pulley at the other end, flexible connections between each pulley and the corresponding support, an endless flexible connection between the driving-pulley and the intermediate pulley, and an endless flexible connection between the intermediate pulley and the first mentioned end pulley and operated by the intermediate pulley.

3. In an embroidering machine, the combination of a main frame, a fabric frame, vertically movable end supports and a vertically movable intermediate support, all guided on the main frame and supporting the fabric frame, a double end pulley adjacent to one of the end supports, a triple pulley adjacent to the intermediate support, a driving-pulley, a flexible connection from each pulley to the corresponding support, an 110 115 120 endless flexible connection between the intermediate pulley and the first named pulley, and an endless flexible connection between the driving pulley and the intermediate pulley.

4. In an embroidering machine, the combination of a main frame, a fabric frame, vertically movable end supports and a vertically movable intermediate support, all guided on the main frame and supporting the fabric frame, pulleys adjacent to the several supports, a flexible connection between each end pulley and the corresponding sup- 125 130

port, a guide pulley vertically above the intermediate pulley, an endless flexible connection guided on the intermediate pulley and said guide pulley and secured to the intermediate support, and endless flexible connections between the end pulleys and the intermediate pulley.

5. In an embroidering machine, the combination of a main frame, a fabric-frame, vertically movable end supports and a vertically movable intermediate support, all guided on the main frame and supporting the fabric-frame, pulleys adjacent to the sev-

eral supports, flexible connections between each pulley and the corresponding support, 15 endless flexible connections between the several pulleys, driving means for one of the end pulleys, and a counterbalance connected to the other of the end pulleys.

In testimony that I claim the foregoing 20 as my invention, I have signed my name in presence of two subscribing witnesses.

KARL EGGART.
